UNITED STATES PATENT OFFICE.

JAMES W. BONTA, OF PHILADELPHIA, PENNSYLVANIA.

TELEPHONE-TRANSMITTER.

SPECIFICATION forming part of Letters Patent No. 352,178, dated November 9, 1886.

Application filed March 11, 1886. Serial No. 194,803. (No model.)

To all whom it may concern:

Be it known that I, JAMES W. BONTA, a citizen of the United States, residing at Philadelphia, in the county of Philadelphia and 5 State of Pennsylvania, have invented certain new and useful Improvements in Telephonic Transmitters, of which the following is a specification, reference being had therein to the accompanying drawings, wherein—

10 Figure 1 is a vertical section, partly in elevation, of a telephonic transmitter embodying my improvements. Fig. 2 is a like view, showing the elevating-table in elevation. Fig. 3 is a front end view, partly sectional, of loose electrode or ball, grooved plate, platform, and its adjusting mechanism. Fig. 4 is a side elevation, partly sectional, of Fig. 3, showing modified form of adjusting mechanism; and 15 Fig. 5 is an end view of ball or loose electrode, platform, and plate, having in cross-section modified form of groove.

My invention has relation to a telephonic transmitter of the form wherein the diaphragm has a fixed electrode for contact with a loose 20 ball or electrode supported upon an inclined plate or table having mechanism for adjusting its inclination to vary the initial contact-pressure between the electrodes; and it has for its object to provide a fixed inclined table 25 adapted to be elevated or depressed, and, if desired, moved toward or away from the diaphragm for varying the contact-pressure of the electrodes without disturbing or altering the inclination of the table.

30 My invention accordingly consists of the combination, construction, and arrangement of parts, as hereinafter described and claimed.

A represents a transmitter box or case having hinged door or front *a*, provided with 35 mouth-piece *a'*. To the door is suitably secured a diaphragm, *B*, having a fixed electrode, *b*, preferably made of carbon.

C is a right-angled bracket, having in its vertical limb a slot, *c*, through which passes 40 a set-screw, *c'*, by means of which the bracket is secured to door *a*, and is adjusted up and down within box *A*. The top of bracket *C* is preferably provided with dovetail or other suitably-formed ways or guides, *c''*, in which 45 50 slides the foot or stem *d* of an inclined platform, *D*, which is firmly held in place on

bracket *C* by set-screw *d'*, which passes through a slot, *d''*, in foot *d*.

Upon the platform *D* rests a carbon block or plate *E*, held in position by set-screws *e*. 55 (Seen more plainly in Fig. 3.) The plate *E* has preferably a longitudinal groove, *e'*, which may be a single groove angular in cross-section, as illustrated in Fig. 4, or a double groove, or two grooves of different widths, to provide two 60 ridges, edges, or tracks, *e''*, for the loose electrode or ball *F* to rest and move upon, and have two or more contacting-points with said plate, as indicated more plainly in Fig. 3.

By adjusting screw *e'* the bracket *C*, and 65 consequently the platform *D*, plate or block *E*, and carbon ball *F* are elevated or depressed to throw a more or less mass or weight of the ball *F* above the axial line of the diaphragm-electrode *b*, and thereby vary the initial contact-pressure of the electrodes, and as the platform *D* has no tilting motion the said contact-pressure is regulated without varying the inclination of plate *E* or platform *D*. By adjusting the set-screw *d'* the platform and plate 70 75 are adjustable to and from the diaphragm after being raised or lowered by the adjustment first above described.

The use of the foregoing double adjustment for platform *D* and plate *E*—or, in other words, 80 their up-and-down and to-and-fro movements—admit of a finer variation of the initial contact-pressure of the electrodes than could be attained if only an up-and-down adjustment is used; but if desired, however, the to-and-fro adjustment may be dispensed with, as 85 shown in Fig. 2, in which case the bracket and platform are secured together or are in one piece.

Instead of using the slot and screw devices 90 shown in Figs. 1, 3, swiveled screws engaging with threaded openings in fixed lugs may be substituted, as indicated in Fig. 5.

Any suitable inductorium, *I*, may be employed, the primary, *1*, of which includes the 95 diaphragm-electrode, ball *F*, plate *E*, and battery *3*, and the secondary, *2*, forms part of the line.

I do not broadly claim in this application means for vertically adjusting without altering 100 the inclination of the table, as that forms the subject-matter of a separate application

filed on even date with this and numbered 194,807.

What I claim is—

- 5 1. In a telephonic transmitter, the combination of a diaphragm having a fixed electrode, a vertically-sliding inclined platform or plate, and a loose ball or electrode resting on said plate in contact with the fixed electrode, substantially as shown and described.
- 10 2. The combination of a diaphragm having a fixed electrode, a loose or ball electrode, a vertical moving platform for the ball, and adjusting mechanism for vertically raising and lowering the ball and platform without varying the inclination of the latter, substantially as shown and described.
- 15 3. The combination, with case A, of diaphragm B, having a fixed electrode, *b*, the vertically-adjustable bracket C, adjustable platform D, having carbon-plate and loose ball or electrode F, substantially as shown and described.

4. The combination of diaphragm B, having fixed electrode, the loose electrode F, and the grooved carbon-plate D, having two or 25 more edges or tracks for contact with the ball, substantially as shown and described.

5. In a telephonic transmitter, the grooved carbon-plate having parallel tracks or edges, as and for the purpose set forth. 30

6. The combination of a diaphragm, a loose ball or electrode, an inclined table, E, and adjusting mechanism for raising and lowering the table without varying its inclination, substantially as set forth. 35

In testimony whereof I affix my signature, in presence of two witnesses.

JAMES W. BONTA.
